UNITED STATES PATENT OFFICE.

JOHN LEE, OF MANSFIELD, OHIO.

POST-HOLE DIGGER.

SPECIFICATION forming part of Letters Patent No. 253,929, dated February 21, 1882.

Application filed October 4, 1881. (No model.)

To all whom it may concern:

Be it known that I, JOHN LEE, of Mansfield, in the county of Richland and State of Ohio, have invented certain new and useful Improvements in Post-Hole Diggers; and I do hereby declare that the following is a full, clear, and exact description of the invention, which will enable others skilled in the art to which it appertains to make and use the same, reference being had to the accompanying drawings, which form a part of this specification.

Figure 1 is a side view of my improved post-hole digger. Fig. 2 is a longitudinal vertical section. Fig. 3 is a horizontal section on the line *x x*. Fig. 4 is a horizontal section on the line *y y*, and Fig. 5 is a detail view of the top of the handle and tamper.

Corresponding parts in all the figures are denoted by like letters of reference.

This invention relates to post-hole diggers; and it consists in certain improvements in the construction of the same, which will be hereinafter fully described, and particularly pointed out in the claims.

In the drawings hereto annexed, A and B represent the main handles or levers of my improved post-hole digger, the lower ends of which are provided with flanged castings or sockets C D, having shoulders E to support the lower ends of the handles. These castings are formed or provided with diverging arms F, to which the digging-blades are attached, as will be hereinafter described. The casting C has an inwardly-projecting arm or plate, G, passing through a slot in the lever A, and into a slot, H, in lever B and socket D, where it is adjustably secured by a thumb-screw, I.

The arms F are provided at their lower ends with transverse notches G², in which the digging blades or spades J are secured by means of set-screws K, or by bolts, or in any other suitable manner.

To the upper end of the lever B is pivoted a cam-lever, L, having an angular slot, M, working upon a stud, N, on the face of the main lever or handle A, and capable of being operated or adjusted by means of a crank or handle, O. By this simple mechanism the levers and spades may be locked in an open or closed position before entering and previous

to being removed from the ground, as the case may be.

The main handle or lever A is provided with notches or marks P to indicate the depth to which the post-hole digger has been forced into the ground.

To the upper end of lever A is attached a chisel or stone-breaker, Q, provided with a socket, Q', by which it is adjusted upon the end of said lever. Said chisel has a transverse opening, S, communicating with a vertical opening, S', in the upper end of the socket, to enable a barbed pin, T, to be driven into the end of the handle, and thus secure the chisel in position. The edge of the chisel is protected by a removable weight, R, which greatly assists the operator in forcing or driving the digger into hard soil, and which also, by inverting the tool, will serve as a rammer or tamper for packing the earth around posts after they have been planted. The chisel serves to break any stones which may be encountered in digging the holes.

From the foregoing description, taken in connection with the drawings hereto annexed, the operation and advantages of my invention will be readily understood. It is simple, convenient, durable, and easily operated. It may be advantageously used for prospecting for minerals or water, for digging wells, and for making holes of any depth by splicing the main lever or handle and operating the lever B by means of a rod or wire attached to the end of cam-lever L. In this case a tamper of considerable weight will be useful in aiding to drive the digger; likewise the device may be employed for making ditches and drains, and for a variety of other purposes.

By disconnecting the handles or levers each may be separately used as a spade for digging purposes.

Having thus described my invention, I claim and desire to secure by Letters Patent of the United States—

1. In a post-hole digger, the sockets C D, having shoulders E, and provided respectively with a laterally-projecting arm, G, and a slot, H, in combination with the handle A and lever B, arranged and operating as herein described, for the purpose set forth.

2. In a post-hole digger, the combination of the handle A, secured to socket C, having laterally-projecting arm G, the handle B, pivoted to said arm, and the cam-lever L, pivoted to handle B, and having an angular slot, M, working upon a stud, N, of handle A, substantially as and for the purpose set forth.

In testimony that I claim the foregoing as my own I have hereto affixed my signature in presence of two witnesses.

JOHN LEE.
